TAG OR THE LIKE FOR ATTACHMENT TO A BOTTLE

James Gilbert Haller, 20 W. Andrew St.,
Lancaster, Pa. 17603

Filed July 7, 1966, Ser. No. 2,969

Term of patent 14 years

(Cl. D1—8)

FIG.4

FIG.1

FIG. 1 is a front elevation of an ornamental attachment for a bottle or the like showing my new design.

FIG. 2 is a reduced scale front elevational view thereof, with a bottle shown in broken lines for illustrative purposes only;

FIG. 3 is a right side elevational view thereof; and

FIG. 4 is a rear elevational view thereof.

I claim:

The ornamental design for a tag or the like for attachment to a bottle, as shown and described.
